US00D669318S

(12) **United States Design Patent**
Bagley

(10) **Patent No.:** **US D669,318 S**
(45) **Date of Patent:** **** Oct. 23, 2012**

(54) **COLLAPSIBLE CONTAINER**

(75) Inventor: **Justin Bagley**, Seattle, WA (US)

(73) Assignee: **Progressive International Corporation**,
Kent, WA (US)

(**) Term: **14 Years**

(21) Appl. No.: **29/411,857**

(22) Filed: **Jan. 26, 2012**

(51) **LOC (9) Cl.** **07-07**

(52) **U.S. Cl.** **D7/629**

(58) **Field of Classification Search** D7/601,
D7/602, 629, 630, 538-542, 584, 586, 587;

(57) **CLAIM**

I claim the ornamental design for the collapsible container, as shown and described.

DESCRIPTION

FIG. 1 is a perspective view of a collapsible container, showing my new design.

FIG. 2 is a top view of the collapsible container.

FIG. 3 is a front view of the collapsible container.

FIG. 4 is a back view of the collapsible container, the left side view being identical.

FIG. 5 is a right side view of the collapsible container; and,

FIG. 6 is a bottom view of the collapsible container.

1 Claim, 4 Drawing Sheets
